To all whom it may concern:

Be it known that I, Samuel Lish, a citizen of the United States, and a resident of Woodmere, Long Island, in the county of Nassau, and State of New York, have invented a new, original, and ornamental Design for a Lady's Hat, of which the following is a specification, reference being had to the accompanying drawing, forming a part thereof, wherein:

The characteristic feature of my design resides in the hat disclosed, comprising spirally wound, upstanding fringe, in association with a plain area on the top of the crown as shown.
